(57) **CLAIM**

The ornamental design for a circular ring caddy, as shown and described.

DESCRIPTION

FIG. 1 is a top, front, right-side, perspective view of a circular ring caddy;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a top, front, right-side, perspective view of an alternate embodiment of the circular ring caddy;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

The broken lines in the figures are for the purpose of illustrating portions of the circular ring caddy and form no part of the claimed design.

1 Claim, 10 Drawing Sheets
